(57) **CLAIM**

The ornamental design for a luminaire, as shown and described.

DESCRIPTION

FIG. 1 is a perspective view of the luminaire from below.

FIG. 2 is a perspective view of the luminaire from above.

FIG. 3 is a bottom plan view of the luminaire.

FIG. 4 is a top plan view of the luminaire.

FIG. 5 shows an elevation view of the left side of the luminaire.

FIG. 6 shows an elevation view of the right side of the luminaire.

FIG. 7 shows an elevation view of the front of the luminaire.

FIG. 8 shows an elevation view of the back of the luminaire; and,

FIG. 9 is a perspective view of the luminaire from above with mounting structure that is not part of the claimed design.

The broken lines are for illustrative purpose only and form no part of the claimed design.

1 Claim, 7 Drawing Sheets
